DISPENSING CABINET

Filed April 16, 1931

UNITED STATES PATENT OFFICE

FLORENCE D. HARRIS, OF FORT THOMAS, KENTUCKY

DISPENSING CABINET

Application filed April 16, 1931. Serial No. 530,553.

My invention relates to dispensing cabinet for tooth paste, shaving cream, and similar articles put up for the market in metal collapsible tubes. One of its objects is to provide a cabinet in which such collapsible tubes may be mounted and housed, and from which the tooth paste or shaving cream may be readily and conveniently discharged from time to time as required. Another object is to provide for conveniently releasing an empty tube and replacing it with a new tube. Another object is to provide for conveniently detaching and cleansing such parts as are liable to come in contact with the tooth paste or shaving cream and conveniently restoring such parts. Another object is to provide an improved sheet metal cabinet for such purpose. My invention also comprises certain details of form and arrangement and combination of components, all of which will be fully set forth in the description of the accompanying drawings, in which:

Fig. 1 is a perspective view of my improved cabinet ready for use.

Fig. 2 is a central vertical section through the same taken on line 2—2 of Fig. 1.

Fig. 3 is a side elevation, partly in section of the tube collapsing shaft detached.

Fig. 4 is a perspective view of the major and minor slides detached.

Fig. 5 is a sectional detail taken on line 5—5 of Fig. 4.

Fig. 6 is a plan of a portion of the rear wall of the cabinet illustrating the manner of attaching the cabinet to a wall or other supporting member.

The accompanying drawings illustrate one embodiment of my invention in which 15 represents a rectangular sheet metal cabinet or housing, preferably formed from a single piece of sheet metal by stamping and folding the same. As illustrated the meeting edges 16 and 17 of the sheet are overlapped at the rear face of the cabinet, and may be locked together if desired by stamped sheet metal tongues 17' from one meeting edge, 17 for instance, passing through perforations 18 in the opposite meeting edge 16. The double thick metal at the meeting edges is also preferably provided with registering stamped

perforations 19 and 20 adapted to detachably engage with two screws 21 and 22 threaded into the wall or other cabinet supporting member 24. If desired the cabinet 15 may be located inside of a medicine cabinet or closet, 55 where it will be shielded from view. As illustrated in Fig. 6, the head of screw 21 is first passed through the enlarged end of perforation 19 and the cabinet moved horizontally relative to the wall to bring the shank 60 of screw 21 to the position in the narrow portion of perforation 19 where the head of screw 22 will register with and enter the enlarged end of perforation 20, whereupon the cabinet 15 is moved in a reverse direction to the 65 position shown in Fig. 6, in which the cabinet is firmly held to the wall against inserting or removing the major slide 25, or the minor slide 26, or removing or replacing one of the tubes 27, and at the same time the cabinet 70 may be readily detached and cleansed if required and then replaced, and the means of attachment is concealed, and is readily placed in position without requiring skilled labor. 75 If desired the screws 21 and 22 may be secured to a transverse spacing strip to space the cabinet forward from the wall 24.

The cabinet 15 is provided with an opening 28 at its lower end through which the tubes are adapted to be introduced and removed. 80 The cabinet 15 is also provided with a vertical slot 29 in one side thereof. A tube collapsing shaft 30 is preferably provided near opposite ends with rollers or discs 31 and 32, 85 preferably of sheet metal, and preferably provided with rubber tires 33 to prevent noise in operation. The rollers or discs 31 and 32 are of nearly the same diameter as the depth of the cabinet from the inside of the front wall to the inside of the rear wall, and hence 90 when the shaft 30 is rotated the rollers or discs 31 and 32 roll downwardly along the front or rear wall, being confined between the front and rear walls. The discs 31 and 32 maintain the shaft 30 at right angles to 95 the side walls. The shaft 30 has a through slot 34 into which the folded end 35 of the tube 27 is inserted, and thereafter upon rotating the shaft 30 the tube 27 is collapsed progressively from its folded end towards 100

its screw-cap end, thereby readily and quickly expelling the tooth paste from time to time as may be required. The collapsed portion of the tube 36 is wound in a spiral upon the 5 shaft 30 as shown in Fig. 2 and may be unwound therefrom when it is desired to detach the tube and replace it with another tube.

One end of the shaft 30 extends through 10 the slot 29 to the exterior of the cabinet where it is provided with a winged head 37 by means of which the shaft 30 may be manually rotated.

A major slide 25 is adapted to be detachably 15 inserted into position to close the opening in the lower portion of the cabinet 15 where the tubes are introduced and removed. The slide 25 is provided with outwardly concave recesses 40 into which corresponding inwardly 20 convex extensions 41 of the cabinet 15 enter and are held yieldingly to retain the slide 25 in place with reference to the cabinet 15. The slide 25 slides vertically into and out of relation to the cabinet 15. The slide 25 is provided 25 with a centrally perforated and threaded projection 42 into which the threaded end 43 of the tube 27 is adapted to be screwed before the slide 25 is slid into relation to the cabinet. The major slide 25 is also provided 30 with downwardly extending stamped projections 44 which form guideways 45 for a minor transversely movable slide 26 which is provided with a perforation 47 to register with the perforation of the projection 42 at one 35 position of the slide 26 and at another position the slide 26 serves to close the lower end of the perforation in projection 42 and prevent escape of tooth paste through the perforation in projection 42 and to protect the 40 tooth paste from dust or other contamination. Both slides 25 and 26 being detachable from the cabinet are readily cleansed before returning to position. When the tooth paste has all been removed from a tube, the slides 45 25 and 26 are drawn downwardly, and the shaft 30 remaining in the cabinet is rotated to unwind the collapsed portion of the tube therefrom. After the collapsed tube and slides have been detached from shaft 30, the 50 tube is unscrewed from the projection 42 and discarded. A new tube is then threaded to the projection 42 and its folded end introduced into the slot 34 of shaft 30, which shaft 30 shows through the opening at the lower end 55 of the cabinet, and thereupon the shaft 30 is elevated in the cabinet 15 and the slides 25 and 26 inserted into place in the cabinet. Though I have illustrated the slide 25 as made of sheet metal, it may however be of cast metal. The 60 opposite ends of slide 26 are turned at right angles thereto to facilitate its operation and prevent its detachment from slide 25. If desired the shaft 30 may be made tubular from sheet metal to reduce its weight, and also the 65 rollers 31 and 32 omitted if desired.

The apparatus herein shown and described is capable of considerable modification within the scope of the claims without departing from the spirit of my invention.

What I claim is:

1. Dispensing apparatus comprising a cabinet having a vertical slot through one side wall thereof and an opening at the lower end thereof for the introduction of a tube of the material to be dispensed, a closure member to 75 which the threaded end of the tube is adapted to be attached and which closure member is adapted to engage and close the opening at the lower end of the cabinet, a spool comprising an axle with rollers near opposite ends thereof and a manually operable member exteriorly of said cabinet, rotatably mounted relative to said cabinet, with one end of said axle projecting through said vertical cabinet slot, said spool axle intermediate of said rollers being provided with means to engage the folded end of a tube, and said spool when being adapted to progressively collapse said tube and to wind the collapsed portion of the tube upon said spool and to expel the contents 90 of the tube from the threaded end of the tube.

2. In a dispensing apparatus of the class described the combination of a cabinet having a vertical slot through one side wall thereof, means at the bottom of the cabinet in which the threaded end of a tube of material to be dispensed is adapted to be held, a spool comprising an axle with discs near opposite ends cooperating with the side walls of the cabinet to retain the axle at right angles to said side walls, one end of the axle extending through the slot in said side wall, the axle, intermediate its ends being provided with means to receive the flattened end of a tube, and means on the extended end of the axle 100 for manually rotating it to progressively collapse the tube by winding it upon said axle. 105

In testimony whereof, I have affixed my signature.

CERTIFICATE OF CORRECTION.

Patent No. 1,845,598.

Granted February 16, 1932, to

FLORENCE D. HARRIS.

It is hereby certified that error appears in the printed specification of the above numbered patent requiring correction as follows: Page 2, line 87, after "when" insert the word rotated; and that the said Letters Patent should be read with this correction therein that the same may conform to the record of the case in the Patent Office.

Signed and sealed this 5th day of April, A. D. 1932.

(Seal)

**M. J. Moore,
Acting Commissioner of Patents.**
